UNITED STATES PATENT OFFICE.

GUSTOV SCHULZ, OF JANSEN, NEBRASKA.

LOCK.

1,164,877.

Specification of Letters Patent. Patented Dec. 21, 1915.

Application filed June 7, 1915. Serial No. 32,788.

To all whom it may concern:

Be it known that I, Gustov Schulz, a citizen of the United States, residing at Jansen, in the county of Jefferson and State 5 of Nebraska, have invented certain new and useful Improvements in Locks, of which the following is a specification, reference being had to the accompanying drawings.

My present invention relates to new and 10 useful improvements in locks and has particular reference to those of the type which are essentially adapted for use in connection with the doors of barns, sheds and similar out buildings.

15 Primarily, it is the object of the invention to provide a lock of this character which will, in case the door is violently pushed or struck from the inside, yield to the impact, permitting the door to open, instead of resisting until the lock is broken.

20 A more specific object of the invention is to provide a lock in which the latch plate carried by the door jamb or post is pivotally secured at one terminal and is, therefore, 25 adapted at times, for swinging movement, but is normally held against such movement and in fixed position to serve as a catch for the spring pressed bolt of the door carried portion of the lock, by means of a 30 wooden rod or hinge pin, which member is adapted to yield in case an abnormal blow is struck the door from the inside of the building, as when a horse in a barn kicks the door.

35 The above, and other incidental objects of a similar nature, which will be herein-after more specifically treated are accomplished by such means as are illustrated in the accompanying drawings, described in 40 the following specification, and then more particularly pointed out in the claims which are appended hereto and form part of this application.

With reference to the drawings, wherein 45 there has been illustrated the preferred embodiment of this invention, as it is reduced to practice, and throughout the several views of which similar reference numerals designate corresponding parts, Figure 1 is a front 50 elevation showing the lock applied to a door, which member together with the adjacent wall of the building, is fragmentarily shown; Fig. 2 is a vertical longitudinal section taken through the lock casing; Fig.

3 is a section on the line 3—3, of Fig. 1; and 55 Fig. 4 is a section on the line 4—4, of Fig. 1.

As best disclosed in Fig. 1 of the accompanying drawings, the lock of the present invention includes generally, a casing A, wherein is slidably mounted, a spring 60 pressed locking bolt B; and a latch plate C which is adapted to form a catch for the locking bolt. The casing A is secured in the door D in a manner which will be next explained and the latch plate is secured to 65 the door jamb E.

The lock casing A consists in a preferably rectangular frame 10, and a pair of face plates 11 and 12 which are secured against opposite sides thereof. The frame 10 is 70 seated in an opening 13 formed in the door, while the face plates are disposed to form closures for this opening and are seated with their edge portions disposed in shallow recesses 14, in a manner best disclosed in Fig. 75 4. Bolts, indicated at 15 are passed through the corners of the face plates and through the intervening portion of the door, for securing the plates and the frame in proper position. The plate 11 is preferably fixed 80 to the frame 10, by being cast as an integral part thereof, although it may be secured thereto by screws, rivets or equivalent fastening devices, if deemed advisable. Extending inwardly from the inner face of the 85 plate 12 and at right angles thereto, are the pegs 16 which are adapted to engage in the four corners of the frame 10 for maintaining the face plate 11 in the proper relation thereto. A screw indicated at 17 may be 90 passed through the plate 11, through the frame 10 and into threaded engagement with the plate 12, if an additional fastening means is desired.

In the outer vertical end wall of the frame 95 10, is formed an opening 18 through which the outer end of the lock bolt B is projected. This lock bolt B is cut-away at its outer end, providing the beveled face 19 as in the ordinary lock bolt and is provided at the inner 100 end of this beveled terminal with a transverse stop shoulder 20 which, by engagement with the end wall of the frame 10, is adapted to limit the outward movement of the locking bolt. As a means for normally holding the 105 bolt in projected position, I employ a helical spring 21 which is interposed between the inner end of the lock bolt and the inner end

wall of the frame 10, being wound at its one end about a stud 22 formed on the lock bolt and at its other end about a stud 23 carried by the inner face of the inner end wall of the frame 10.

Upon the upper face of the lock bolt are a plurality of rack teeth 24 which are engageable by the teeth of a mutilated pinion 25. This member 25 is keyed upon or cast integrally with an axle 26, the terminals of which are journaled in horizontally aligned openings 27 formed in the plates 11 and 12, as in Fig. 4. The terminals of the axles project beyond the fixed plates and are provided with transverse bores or openings 28, wherein may be secured the trunnions 29 formed on the terminals of the handles 30. A handle 30 is thus provided for each side of the door. Obviously, as will be seen upon reference to Fig. 3, either of the handles may be turned to retract the lock bolt and disengage this member from the latch plate which will be next described.

The latch plate heretofore designated as an entirety, by the letter C, includes three sections 31, 32 and 33. The member 31 is substantially T-shaped and is arranged with its head portion 34 in vertical position. Integral sleeves or tubes indicated at 35 and 36 are formed at the ends of the stem portions 37 of the member 31 to receive the pins 38 and 39, which members also pass through tubes or sleeves 40 and 41 formed on the terminals of the members 32 and 33. The pin 38, which passes through the sleeve 41 is formed preferably of steel, while the pin 39 which passes through the sleeve 40 is preferably formed from wood. The plates 32 and 33 are each provided with a pair of longitudinally extending slots 42, through which lag screws are passed and threaded into the door jamb or post, for holding the plates in position thereon. By providing slots, instead of circular openings for the lag screws, it is possible to adjust the latch plate upon the door, without moving the screws.

When the latch plate has been properly attached to the door post in the manner shown best in Fig. 1, the vertically extending head portion 34 of the plate 31 projects beyond the face of the door jamb and in the path of the projecting terminal of the lock bolt, as in Fig. 4.

The actual construction and arrangement of the several parts of the invention, being thus disclosed, it now remains to describe briefly the manner in which the device is operated. Referring, therefore, to Fig. 4 it will be seen that when the door is swung inwardly to closed position, the beveled face 19 of the lock bolt will ride over the outer edge of the member 34, until the bolt is passed inwardly of this member and has again been projected by the spring 21 to engage against the inner face of the member

34. The door is thus locked against movement until one of the handles is turned to retract the locking bolt. In case the door is kicked from the inside by a horse or through any source subjected to an abnormal blow or impact, it is obvious that the lock embodied herein will not resist the blow to the extent that the lock will, itself, be broken. If the blow or impact is of sufficient force to break an ordinary lock, the wooden pin 39 will break, allowing the plate 34 to swing outwardly, thereby permitting the door to open.

In reduction to practice, it has been found that the form of this invention illustrated in the accompanying drawings, and referred to in the above description as the preferred embodiment is the most efficient and practical; yet realizing that the conditions concurrent with the adoption of this device will necessarily vary, it is desirable to emphasize the fact that various minor changes in the details of construction, proportion and arrangement of parts may be resorted to, when required, without sacrificing any of the advantages of this invention, as defined by the appended claims.

What is claimed is:—

1. The combination with a lock having a projectable lock bolt, of a latch plate, said latch plate including a base section, a section pivotally attached thereto, and a member normally maintaining the second mentioned section against movement, said second mentioned section being engageable by the lock bolt, and being relatively inflexible, but of a nature to break, allowing the pivoted end to swing outwardly and release the bolt in case the door to which the bolt is secured is subjected to an abnormal force.

2. A latch plate for locks including a pair of plates fixed adjacent the door to which the lock is applied, a T-shaped section pivotally attached to the fixed sections, the T-shaped section being engageable by the bolt of the lock, and a member connecting the T-shaped section and the fixed sections, whereby the T-shaped section is normally held against movement, said member being adapted to break under a force less than the force required to break the lock.

3. A latch plate for locks including two similar plate sections, each provided with elongated horizontally disposed slots, lag screws passing through the slots for securing the plate sections to a supporting structure, tubes formed at each end of each plate section, said plates being arranged in parallel spaced relation and being disposed with their corresponding tubes in transverse alignment, a T-shaped plate section having its stem disposed between the fixed plate sections, said stem being provided at each end with a tube, the tubes of the stem being disposed to align with the tubes of the fixed plate sections, a metallic hinge pin passing

through the tubular members at the outer ends of the fixed plate sections and through the alined tube of the stem member, whereby the T-shaped plate section is pivotally attached to the fixed plate sections, and a breakable hinge pin passing through the tubes at the inner ends of the fixed plate sections and the stem member, for normally holding the T-shaped plate section against swinging movement, said breakable member being adapted to yield under a force less than the force required to break a lock employed in connection with the latch plate.

4. A latch plate for locks including two similar plate sections adapted to be secured to a supporting structure, tubes formed at each end of each plate, a T-shaped plate section having its stem disposed between the plate sections, said stem being provided at each end with a tube, a metallic pin passing

through the tubes at the corresponding terminals of the plate sections and stem, for pivotally uniting the plates and stem, and a non-metallic pin passing through the tubes at the other ends of the plate sections of the stem member for normally holding the T-shaped plate section against swinging movement, said non-metallic pin being adapted to break under a force less than the force required to break the lock employed in connection with the latch plate, said T-shaped plate being adapted to swing and release the lock immediately upon the breaking of said non-metallic pin.

4. A latch plate for locks including two similar plate sections adapted to be secured to a supporting structure, tubes formed at each end of each plate, a T-shaped plate section having its stem disposed between the plate sections, said stem being provided at each end with a tube, a metallic pin passing

through the tubes at the corresponding terminals of the plate sections and stem, for pivotally uniting the plates and stem, and a non-metallic pin passing through the tubes at the other ends of the plate sections of the stem member for normally holding the T-shaped plate section against swinging movement, said non-metallic pin being adapted to break under a force less than the force required to break the lock employed in connection with the latch plate, said T-shaped plate being adapted to swing and release the lock immediately upon the breaking of said non-metallic pin.

In testimony whereof I hereunto affix my signature in the presence of two witnesses.

GUSTOV SCHULZ.
